UNITED STATES PATENT OFFICE.

SARA ARABELLE KELCHNER, OF NEW YORK, N. Y.

DESIGN FOR A STUFFED DOLL.

Application filed January 7, 1927. Serial No. 20,302. Term of patent 14 years.

To all whom it may concern:

Be it known that I, SARA ARABELLE KELCHNER, a citizen of the United States, residing at 141 Washington Place, New York city, in the county of New York and State of New York, have invented a new, original, and ornamental Design for a Stuffed Doll, of which the following is a specification, reference being had to the accompanying drawings, forming part thereof, in which

I claim:

The ornamental design for a stuffed doll substantially as shown and described.

SARA ARABELLE KELCHNER.
